(Cl. D22—3)

FIG. 1.

FIG. 2.

FIG. 3.

FIG. 4.

FIG. 1 is a side perspective view of a casing for an electric shaver;

FIG. 2 is a bottom plan view thereof;

FIG. 3 is a perspective view of the side opposite that shown in FIG. 1; and

FIG. 4 is a side elevational view thereof.

The broken line showing of the cutting blades is for illustrative purposes only. The dominant feature of my design resides in the integral handle and casing head shown in full lines.

I claim:

The ornamental design for casing for an electric shaver, substantially as shown and described.
